UNITED STATES PATENT OFFICE.

EDGAR KNAPP AND CARL GODFREY ALLGRUNN, OF MIDDLEPORT, NEW YORK.

CROP DUSTER.

Application filed April 17, 1923. Serial No. 632,751.

To all whom it may concern:

Be it known that we, EDGAR KNAPP and CARL G. ALLGRUNN, both citizens of the United States, and residents of Middleport, in the county of Niagara and State of New York, have invented a new and Improved Crop Duster, of which the following is a full, clear, and exact description.

The present invention relates to new and useful improvements in machines for dusting crops, and it pertains more particularly to a device of this character especially adapted for personal wear by the operator.

It is one of the objects of the invention to provide a relatively small portable duster adapted, through the medium of a suitable harness, to be strapped to the person of the operator for the purpose of distributing insecticides in powdered form.

It is a further object of the invention to provide a device of this character which is pneumatically operated.

It is a further object of the invention to provide a device of this character in which an insecticide compartment and a blower compartment are provided in a single body portion or housing.

It is a further object of the invention to construct a device of this character in such a manner that the several parts thereof are readily accessible for repair.

It is a still further object of the invention to construct the device in such a manner that a single driving crank operates both the insecticide feed and the blower.

With the above and other objects in view, reference is had to the accompanying drawings, in which

Figure 1 is a transverse sectional view taken on the line 1—1 of Fig. 2;

Fig. 2 is a longitudinal vertical sectional view taken on the line 2—2 of Fig. 1;

Fig. 3 is a horizontal sectional view;

Fig. 4 is a view in elevation of the device.

Referring more particularly to the drawings, the device comprises a housing or the like, 5, and such housing is divided into two compartments 6 and 7, by means of a suitable partition 8.

One end wall of the housing 5 is provided with a cap 9, and this cap 9 serves as the support for the bearing 10. The opposite end wall is provided with an opening 11 adapted to be closed by means of a plate 12, which plate is secured in position by means of screws or the like, 13. The plate

12 is positioned with a bearing member 14, which, together with the bearing 10, forms the end supports of a shaft 15.

Mounted in the compartment 6 and removably secured to the partition 8, is a housing 16. Mounted in this housing 16, is a plurality of gears 17, 18, 19, 20 and 21. The gear 17 is caused to rotate with the shaft 15 by means of a key 22. The gear 18 is carried by a shaft 23, and adapted to rotate with the shaft 23 is the gear 19. The gear 19 is adapted to drive the gear 20 through the medium of a small gear 24 mounted on a stud shaft 25, and the gear 20 is adapted to drive the gear 21. The complete set of gearing is shown in Fig. 1 in dotted lines.

The gear 21 is carried by a sleeve 26 mounted upon the shaft 15 by means of bearings 27. This sleeve has a plurality of fan blades 28 secured thereto, said fan blades being mounted in the compartment 7, and through the medium of the gearing said blades are adapted to be rotated within the compartment 7, which compartment forms the fan housing of the device. Closing the gear housing is a plate 29, which is secured to the housing by means of screws 30, and such plate serves to exclude dust or other foreign matter from the housing 16.

Secured to the shaft 15, by a cotter pin or the like, 31, is an agitating device. This agitating device has a hub portion 32, through which the cotter pin 31 passes to key it to the shaft, and projecting from the hub portion 32 are arms 33, which arms have angularly disposed forked extensions 34. Mounted in one of these angularly disposed extensions 34, is an agitator 35, and carried by each of the arms 33 is an agitator 36, the outer face of which carries a rubbing element 37, the purpose of which will be hereinafter described.

The bottom wall of the receptacle 6 is curved as indicated by the reference character 38, and said curved bottom wall is provided with a plurality of perforations 39, through which material is forced by means of the rubbing elements 37 carried by the arms 33.

Adapted to regulate the volume of material discharged from the compartment 6, through the openings 39, is a sliding plate 40, and such sliding plate is operated by means of a handle portion 41.

The blower compartment 7 is provided

with a discharge opening 42, and such discharge opening has a passage 43 leading therefrom, which passes beneath the openings 39 in the bottom of the compartment 6, 5 as more clearly shown in Figs. 2 and 3. This discharge is arranged so that the draft of air generated in the compartment 7 will be forced therethrough beneath the discharge of the compartment 6 and will pick up material discharged through the openings 39 therein.

The compartment 6 has a cover preferably of the hinge type and designated by the reference character 44, and by this means 15 material in the form of powdered insecticide is introduced into the compartment 6.

Secured to the free end of the shaft 15 is an operating crank 45, which is provided with a handle 46 by means of which the 20 shaft 15, the gearing within the housing 16, and the fan blades are rotated.

The device is carried upon the person by a suitable harness (not shown) and is adapted to be engaged with lugs or the like 50, 25 carried by the receptacle, and leading from the discharge 43 is a spout or the like, 51, through which the material is discharged by the machine.

To aid in steadyng the device in operation, it is provided on its front wall with a handle 52 adapted to be grasped by the operator.

The device operates in the following manner:

35 The compartment 6 is filled with insecticide in powdered form and after it has been strapped in position upon the operator, the crank 45 is turned by means of the handle 46 in a clockwise direction. This 40 action causes the gear 17 to move the gear 18 together with the gear 19 in an anti-clockwise direction. Engagement of the gear 19 with the gear 24 causes the gears 20 and 24 to move in a clockwise direction and the 45 engagement of the gear 20 with the gear 21 causes the gear 21 to move in an anti-clockwise direction, which is the direction of travel of the fan blades 28. Movement 50 of the fan blades in this direction generates a draft of air through the discharge 43 beneath the discharge openings 39 of the compartment 6. Simultaneously with the driving of the gears through the medium of the shaft 15, the agitating device is moved 55 through the compartment 6 and the material is at all times agitated in order that it may be more readily discharged from the compartment 6. As the material is positioned upon the discharge openings 39, it is rubbed therethrough by means of the rubbing elements 37 and passes into the path of the draft through the discharge 43 and is picked up by the draft of air passing through said discharge and is subsequently discharged 60 from the spout 51 which is capable of ma-

nipulation by the operator in order that the discharge of the material from the device may be directed at the will of the operator. The volume of material discharged from the compartment 6 may also be regulated at the 70 will of the operator, by the plate 40 to determine the number of openings 39 through which the material will be permitted to pass.

From the foregoing it is apparent that the present invention provides a device of 75 this character in which it is possible to vary the volume of material discharged from the device. Furthermore, due to the wiping action of the wiping elements, the material is caused to be discharged from its compartment and due to the position of the discharge 80 of the blower compartment the material is discharged directly into the path of air discharged from the blower compartment.

What is claimed is:

1. A device of the character described comprising a housing, a partition dividing said housing into a blower compartment and an insecticide compartment, a fan mounted in the blower compartment, a shaft extending longitudinally of said housing, a gearing adapted to be driven by said shaft for the purpose of driving the fan in the blower compartment, and a gear housing for supporting said gearing, said gear housing being removably carried by the partition of the first-mentioned housing. 85

2. A device of the character described comprising a housing, partition dividing said housing into a blower compartment and an insecticide compartment, a shaft extending longitudinally of said housing and through both of said compartments, a gearing for driving said blower and interposed with respect to the blower and the shaft, said gearing being driven by said shaft, and a housing for supporting said gearing, said housing being supported by the partition dividing the first-mentioned housing into the blower and the insecticide compartments. 100

3. In a device of the character described, a housing divided into compartments, one of which constitutes a blower compartment and the other an insecticide compartment, a fan mounted in said blower compartment a shaft extending longitudinally of said housing a gearing operated by said shaft and serving as the blower operating means, means for driving said gearing to operate the blower a plurality of bearings for loosely mounting said blower on said shaft and independently thereof, and means removably carried by the opposite ends of the first-mentioned housing for supporting said longitudinally extending shaft therein. 115

4. In a device of the character described, a housing divided into compartments, one of which comprises a blower compartment, the other comprising an insecticide compartment, a fan mounted in said blower com- 130

partment, a shaft extending through said housing and serving the means for mounting said fan, and a gearing operated by said shaft and serving to drive said fan, said gearing being supported from one of the walls of the insecticide compartment.

5. In a device of the character described, a housing divided into a blower compartment and an insecticide compartment, a

shaft extending longitudinally of said housing, a fan loosely supported on said shaft in the blower compartment, a gear housing supported on one of the walls of the insecticide compartment, and a fan operating gearing mounted in said gear housing, 15 said gearing being operated by said shaft.

EDGAR KNAPP.

CARL GODFREY ALLGRUNN.
